FREDERICK WILLIAM HULSE, OF NORTHFIELD, NEAR BIRMINGHAM, ENGLAND,
ASSIGNOR OF ONE-HALF TO ARMES AUTOMATIQUES LEWIS, OF ANTWERP, BELGIUM.

CARTRIDGE-EXTRACTOR FOR FIREARMS.

1,352,515.

Specification of Letters Patent. Patented Sept. 14, 1920.

Application filed March 26, 1918. Serial No. 224,764.

To all whom it may concern:

Be it known that I, FREDERICK WILLIAM HULSE, a subject of the King of Great Britain and Ireland, residing at "Northwood," Bristol Road, Northfield, near Birmingham, in the county of Warwick, England, have invented certain new and useful Improvements in or Relating to Cartridge-Extractors for Firearms, of which 10 the following is a specification.

This invention relates to extractors fitted to the breech blocks of rifles, automatic machine guns or other fire-arms.

The object of the invention is to enable 15 the extractor to be more easily fitted to the breech block and to increase its durability or life under severe and quickly repeated stresses to which the extractor in many modern fire-arms is subjected.

20 The extractor is of the type shown in the U. S. patent to Mauser, No. 431,670, July 8, 1890.

The present invention consists in making the extractor proper and its spring in 25 two separate pieces, adapted to be mounted on the breech block in such manner that the one is constrained or retained in place by the other.

The invention further consists in arranging the two said separate pieces relative to 30 the breech block in such a manner that the required elastic radial movement of the hook-like end of the extractor proper may take place with a smaller distortion of its 35 spring, and that a greater effective length of spring blade may be provided.

I append drawings illustrating my invention:—

Figure 1 being a longitudinal sectional 40 view;

Fig. 2 a plan; and

Fig. 3 a transverse vertical sectional view.

In carrying the invention into effect, the extractor proper 3 is made of a rigid piece 45 of steel, having a hook-like end 1 and locating pin 2 adapted to engage a recess 2^a in the breech block 2^b. A short part of the outer surface of the extractor, near the hook-like end, lies normally flush with the outer 50 cylindrical surface of the breech block, as shown. The bottom 4 of the extractor is flat and normally lies in contact with the flat bottom 4^b of the slot in the breech block. On its outer surface a shoulder 5 is formed 55 behind the said short part 3^a flush with the

breech block, the thickness gradually diminishing toward the rear end 6. The rear end 7 of the spring blade 10 is relatively thick and is shaped, as before, to engage with the undercut slot in the breech block. 60 The forward free end 8 of the spring abuts against the said shoulder 5 of the extractor and presses the latter radially inward. The outer surface of the spring blade is, as before, normally flush with that of the breech 65 block, its inner surface from its free end being just clear of the extractor.

The spring is in the form of a cantilever blade and is inserted in position by sliding it along the slot in the breech block, the 70 flange 9 being held by the undercut portion of the slot in the breech block as aforesaid. The extractor is next inserted with its rear end 6 underneath the free end 8 of the spring blade, pushed along the slot in the 75 breech block, its hook-like end 1 being forcibly pushed radially outward until the end of the locating pin 2 rests on the bottom of the said slot. When pushed home the locating pin 2 drops into the corresponding hole 80 2^a in the breech block, retaining both the extractor and the spring blade in the slot of the breech block.

When the hook-like end of the extractor is moved radially outward as it slides over 85 the flanged base of the cartridge, the extractor oscillates radially outward through a small angle about its rear end 6 as a fulcrum resting on the bottom of the breech block. The corresponding radial displacement of the free end 8 of the spring blade 90 is less than that of the hook-like end of the extractor.

Thus the total angle of elastic distortion of the spring is decreased by the present invention, and as a greater volume of steel 95 can be effectively employed to take up the said elastic distortion the maximum stress on the spring under the severe conditions of service is reduced and the risk of fracture 100 is therefore reduced to a minimum.

Having now fully described and ascertained my said invention and the manner in which it is to be performed, I declare that what I claim is:—

1. In a fire-arm, the combination with a breech block having a peripheral slot into which merges a recess and undercut portions which are formed in the breech block, of an extractor having a locating pin engaging 110

said recess and provided at its forward end with a hook-shaped part adapted to engage the flange of a cartridge, the rear end of said extractor resting upon the bottom of 5 said slot, and a leaf-spring member having a projecting part to engage the under cut portions of the breech block, one end of said spring member engaging an intermediate portion of said extractor.

10 2. In a fire-arm, the combination with a breech block, of a cartridge extractor carried by the breech block and having a hook-shaped front end, the outer surface of the extractor being provided with a shoulder

from which the outer surface is inclined 15 down to the rear end of the extractor, and a leaf-spring member having its rear end secured to the breech block, the under surface of the spring member being inclined from its front end down to the rear portion of the member, and the rear end of the extractor resting on the breech block and the front end of the spring member resting upon the inclined surface of the extractor. 20

In testimony whereof I have signed my 25 name to this specification.

FREDERICK WILLIAM HULSE.
